UNITED STATES PATENT OFFICE

JOSEPH E. BRIGHT, OF ST. LOUIS, MISSOURI.

FILTER.

SPECIFICATION forming part of Letters Patent No. 506,304, dated October 10, 1893.

Application filed May 26, 1893. Serial No. 475,615. (No model.)

To all whom it may concern:

Be it known that I, JOSEPH E. BRIGHT, of St. Louis, Missouri, have made a new and useful Improvement in Filters, of which the following is a full, clear, and exact description.

The improvement relates more especially to the strainer through which the filtered water passes as it leaves the filter, and it consists in the mode of constructing the strainer, substantially as is hereinafter set forth and claimed, aided by the annexed drawings, making part of this specification, in which—

Figure 1 is a sectional elevation of a filter having the improvement; the preferred arrangement of the alum-pot is indicated in broken lines; Fig. 2 a vertical section of one of the strainers; Fig. 3 a plan of the strainers and their connections, and Fig. 4 a view showing the parts of the strainer-chamber in vertical section and separated from each other.

The views are not all upon the same scale.

The same letters of reference denote the same parts.

A represents an ordinary filter saving as modified or supplemented by the improvement under consideration.

B represents the pipe through which water is supplied to the filter. In the present arrangement the pipe B leads into a side pipe C which in turn, and at the upper end c thereof connects with the interior of the filter, above the filter-bed D, in the ordinary manner, and whose lower end c' connects with the pipe E through which the filtered water is discharged from the filter.

F and G represent valves in the side pipe C and respectively at opposite sides of the point of the connection of the pipe B therewith, and H represents a valve in the pipe E at the outer side of the point of the connection of the pipe C therewith.

I represents the waste pipe.

An air escape valve is shown at J and K represents a removable plug in the casing of the filter.

The alum-pot is indicated at L, and l and l', represent the pipes used to connect the pot with the side pipe C, and respectively above and beneath the position of the valve F there-in, and l², l³, represent valves in the pipes l, l', respectively. The water-pipe has a valve i.

The improved strainers are shown at M.

One, two, or more of them may be used. In the present illustration a system of four strainers is shown. They are arranged to deliver the water passing them into the pipe E. Now my object is to provide for readily and economically constructing the strainers, and to this end the parts composing the strainer-chamber are adapted to be combined and held in position by means of appliances easily obtainable. The parts referred to are shown at m, m'. They are semi-spherical substantially, the lower one, m', being preferably somewhat deeper than the upper one, and they are each provided with a flange m², and each of them has perforations m³, which taper from the interior of the chamber outwardly, all substantially as shown. To form and sustain the strainer-chamber the parts m, m', are arranged as shown in Fig. 2; the flanges m², m², of the two parts respectively are placed together and are held between the end of the threaded tube N and the inwardly-turned flange o of the cap O which engages with and is adapted to be screwed upward and downward on the tube N, substantially as shown. That is, the strainer-chamber, containing the gravel or shot, P, and the tube N and cap O, combined as shown in Fig. 2, constitute the improved strainer, and it is held in place by screwing the lower end of the tube N into an elbow, Q, or any equivalent tubular part, and preferably until the lower end of the cap O, meets the upper end of the elbow, substantially as shown in Figs. 1 and 2. The elbows, Q, which sustain the strainers shown, are united by means of tubes q and the cross q', and the cross, in the present illustration connects, by means of the tube q, with the T, q², which supports the strainer as shown, and the T in turn is joined to the pipe E, which passes out through the shell of the filter in the ordinary manner. The described support of the strainers is preferably embedded in grouting, R, which is placed in the bottom of the filter as shown. The strainer-parts in practice are made of sheet-copper, and the perforations, m³, are formed by punching the sheet from the inner side thereof.

In operation, the valves G and i are closed and the valves F, H, are opened, and the water then flows to the filter and passes downward through the filter-bed and thence

through the strainers into the discharge pipe E. The water is filtered by passing through the filter-bed, and the strainers prevent the sand of the filter-bed, or whatever the filter-bed is composed of, from being carried into the discharge pipe. The sand cannot very well pass into the strainer-chamber, and if any portion of it does pass thereinto it is arrested within the strainer-chamber by means of the gravel P. When it is desired to cleanse the filter the valves F, H, are closed and the valves G and i are opened, and the water then flows from the pipe B through the lower part of the pipe C into the pipe E and thence upward through the strainers into the filter-bed, and passing upward through the filter-bed it agitates the same and carries off the dirt with it and is discharged through the waste-pipe. The shape of the perforations in the lower part of the strainer-chamber hinders the dirt, if any, in the pipe E, and the other pipes leading to the strainers, from passing upward into the strainer-chambers. If at any time it is desired to open the strainer-chambers the caps O, are unscrewed from the tubes, N, leaving the strainer parts free to be separated from each other and to be lifted out of the tubes,

N, an operation readily performed. It is desirable for the upper one of the strainer-parts to be crowned substantially as shown as there- 30 by a space, m^5 , is provided above the gravel P for the filtered water to enter and occupy before passing to the valve beneath.

I claim—

1. The herein-described filter-strainer consisting of the chamber-parts perforated and flanged as described, the threaded tube, and the flanged threaded cap, the flanges of said chamber-parts being held between the end of said tube and the flange of said cap as described. 35

2. The combination of the strainer-parts m , m' , perforated, flanged and shaped as described, the threaded tube N, the flanged and threaded cap O, and the elbow Q, the flanges 40 of said strainer parts being held between the end of said tube and the flange of said cap, and said strainer being sustained upon said elbow substantially as described. 45

Witness my hand this 22d day of May, 1893.

JOSEPH E. BRIGHT.
